Littenberg, Krumholz & Mentlik, LLP(57) **CLAIM**

The ornamental design for a case for battery module, as shown and described.

DESCRIPTION

FIG. 1 is a front perspective view of a case for battery module according to our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged perspective view of portion "8" shown in FIG. 7; and,

FIG. 9 is an enlarged perspective view of portion "9" shown in FIG. 7.
